UNITED STATES PATENT OFFICE.

H. M. HAMILTON, OF FRANKLIN, PENNSYLVANIA.

IMPROVED DEVICE FOR COLLECTING GASES FROM PETROLEUM AND OTHER WELLS.

Specification forming part of Letters Patent No. 43,201, dated June 21, 1834.

To all whom it may concern:

Be it known that I, H. M. HAMILTON, of Franklin, in the county of Venango and State of Pennsylvania, have invented a new and Improved Apparatus for Separating and Securing the Gases emanating from Petroleum, Salt, and other Wells; and I do hereby declare that the following is a full, clear, and exact description of the same, reference being had to the accompanying drawings, making a part of this specification, in which—

Figure 1 represents a vertical central section of my invention. Fig. 2 is a plan or top view of the same.

Similar letters of reference indicate corresponding parts in both figures.

This invention consists in the application to the upper end of the pipe or stock used for pumping petroleum, salt, and other wells of a chamber or series of chambers with two discharge-openings, one at or near the bottom, through which the liquids which are brought up from the well descend to be conducted to their appropriate receptacle or tank, and the other opening in the top of said chamber, through which the gases emanating from the well ascend to be conveyed to a tank or other proper vessel, from which they can be drawn and used for fuel or illumination.

To enable those skilled in the art to fully understand and construct my invention, I will proceed to describe it.

A represents the tube or stock of a pump which serves to pump petroleum, salt, or other liquid from a well. This pump is provided with a plunger, B, and its piston-rod C extends upward through the chamber D and connects with a suitable lever or working beam, or with any other suitable mechanism by means of which a reciprocating motion can be imparted to the plunger. The chamber D is secured to the top end of the pipe A, so that the liquid, which is raised by the pumping operation, discharges from said pipe immedi-

ately into the chamber. This chamber is provided with two apertures, a b, one at the bottom and the other at the top, and pipes c d lead from said apertures to suitable tanks or vessels. The liquid which is raised by the pump collects at the bottom of the chamber D and discharges through the aperture a and pipe c, being collected in a suitable tank for future use. The gaseous products and vapors rising from the well with the liquid also collect in the chamber A, and they escape through the aperture b in the top of said chamber and are conducted through the pipe d to a suitable tank or reservoir, from which they can be drawn to be used for fuel or for illuminating purposes.

The separation of the gaseous from the liquid products of a well is thus effected in the simplest possible manner, no costly apparatus being required, and the operation of pumping up the liquid from the well is not interfered with, and can be conducted precisely in the same manner as with an ordinary pump. The gaseous products, which usually are allowed to escape in the open air, are collected and can be used with advantage as above stated, and at the same time, by evaporating the gases from the liquids, the operation of distilling or evaporating said liquids is facilitated and the danger of an explosion is averted.

What I claim as new, and desire to secure by Letters Patent, is—

The application to the pipe or stock A of a pump used for pumping petroleum, salt, or other wells of a chamber, D, with two apertures, a b, one at the bottom to carry off the liquid and the other at the top to carry off the gases, in the manner substantially as herein specified.

H. M. HAMILTON.
